United States Patent Office

Des. 206,360
Patented Nov. 29, 1966

206,360

POURING SPOUT FOR A JAR OR THE LIKE

Louis E. Pastorius III, 2133 Brownsville Road,
Pittsburgh, Pa. 15210

Filed Jan. 26, 1965, Ser. No. 83,577

Term of patent 14 years

(Cl. D58—26)

Fig. 1.

Fig. 2.

FIG. 1 is a front perspective view of a pouring spout for a jar or the like showing my new design;

FIG. 2 is a rear perspective view thereof.

I claim:

The ornamental design for a pouring spout for a jar or the like, substantially as shown.
